[57] CLAIM

The ornamental design for an easel spice rack, as shown and described.

DESCRIPTION

FIG. 1 is a perspective view of an easel spice rack showing my new design, with the broken lines showing matter for illustrative purposes only and forming no part of the claimed design;

FIG. 2 is a front elevational view of the easel spice rack;

FIG. 3 is a rear elevational view of the easel spice rack;

FIG. 4 is a top plan view of the easel spice rack;

FIG. 5 is a right side elevational view of the easel spice rack;

FIG. 6 is a left side elevational view of the easel spice rack;

and,

FIG. 7 is a bottom plan view of the easel spice rack.
